The ornamental design for an electronics enclosure for holster, as shown and described.

DESCRIPTION

FIG. 1 is a front perspective view of the electronics enclosure for holster of the present invention;

FIG. 2 is a front view of the electronics enclosure for holster of the present invention;

FIG. 3 is a rear view of the electronics enclosure for holster of the present invention;

FIG. 4 is a right side view of the electronics enclosure for holster of the present invention;

FIG. 5 is a left side view of the electronics enclosure for holster of the present invention;

FIG. 6 is a top view of the electronics enclosure for holster of the present invention;

FIG. 7 is a bottom view of the electronics enclosure for holster of the present invention; and,

FIG. 8 is a rear perspective view of an embodiment of the electronics enclosure for holster of the present invention. The broken lines depicting a data port in FIGS. 3 and 8, and screw holes in FIGS. 1, 4, 5, and 8, depict structural portions of the electronics enclosure for holster that form no part of the claimed design.
